UNITED STATES PATENT OFFICE.

MATTHEW C. DAY, OF PROVIDENCE, RHODE ISLAND.

DESIGN FOR A MEDICINE-SPOON.

SPECIFICATION forming part of Design No. 34,314, dated April 2, 1901.

Application filed March 11, 1901. Serial No. 50,766. Term of patent 14 years.

To all whom it may concern:

Be it known that I, MATTHEW C. DAY, a citizen of the United States, residing at Providence, in the county of Providence and State of Rhode Island, have invented and produced a new and original Design for a Medicine-Spoon, of which the following is a specification, reference being had to the accompanying drawings, forming part thereof.

10 Figure 1 is a plan view of a medicine-spoon, showing my new design. Fig. 2 is an end view of the same. Fig. 3 is a longitudinal sectional view, and Fig. 4 is a transverse section through the bowl.

15 As shown in the drawings, the leading or material feature of my design consists in the ovate oblong shape of the bowl, terminating at the end in a downward and sideward extending lip, from which convex marginal lips extend along each side of the bowl to the base

of the handle. The bowl is of semicircular cross-section. The marginal lips extend from the margin of the bowl inward, as is shown in Fig. 4, and unite in a point at the base of the handle. The end lip surrounds the outlet- 25 opening and merges into the marginal lips, as is shown in Fig. 2.

Having thus described my invention, what I claim as new, and desire to secure by Letters Patent, is—

30 The design for a medicine-spoon as herein shown and described.

In testimony whereof I have signed my name to this specification in the presence of two subscribing witnesses.

MATTHEW C. DAY.
